UNITED STATES PATENT OFFICE.

JOHN SONTHEIMER, OF LINCOLN, NEBRASKA.

HINGE FOR DAVENPORTS OR SOFA-BEDS.

1,044,280.

Specification of Letters Patent.

Patented Nov. 12, 1912.

Application filed February 5, 1912. Serial No. 675,449.

To all whom it may concern:

Be it known that I, JOHN SONTHEIMER, a citizen of the United States, and a resident of Lincoln, in the county of Lancaster 5 and State of Nebraska, have invented new and Improved Hinges for Davenports or Sofa-Beds, of which the following is a full, clear, and exact description.

The object of the invention is to provide 10 a new and improved hinge structure for use with sofa beds adapted to properly connect the seat and back frames and the base, and at the same time admit of easy manipulation of the front and back in moving 15 the same from one position to another.

A further object of the invention is the arrangement of an improved hinge structure including a pawl designed to be moved pivotally and longitudinally, and engage a 20 plurality of stops or pins, whereby the seat and back associated with the pawl may be adjusted to any angle in respect to each other and locked in their adjusted positions.

In carrying out these objects, a base of 25 any desired construction is provided which has associated therewith a back and seat frame. The back and seat frames are pivotally connected and in addition are pivotally mounted on suitable guiding links. The 30 pivotal movement of the frames is controlled and regulated by a pawl pivoted to the seat frame and arranged to engage a pin or stop in the back frame. The pawl in addition to acting as a locking means is formed 35 with a disengaging member whereby when the seat is moved to a predetermined position the pawl is disengaged for permitting the two frames to act independently in order that they may be moved so as to occupy the 40 same horizontal plane.

A practical embodiment of the invention is represented in the accompanying drawings forming a part of this specification, in which similar characters of reference 45 indicate corresponding parts in all the views.

Figure 1 is a side view of a davenport or sofa bed embodying the invention; Fig. 2 is a longitudinal central vertical section 50 through Fig. 1; Fig. 3 is a fragmentary side view of one of the hinges and surrounding parts of the frame showing the pawl in its disengaged position; Fig. 4 is an edge view of the structure shown in Fig. 3; Fig. 5 is a view similar to Fig. 3, but showing the pawl in its position just previous to that

shown in Fig. 3; Fig. 6 is a view similar to Fig. 3 except that the seat is shown as partially lowered and the pawl in an inoperative position; and Fig. 7 is a fragmentary longitudinal vertical section through the structure shown in Fig. 1 after the same has been moved to a complete open position for use as a bed.

Referring to the accompanying drawings 65 by numerals, 1 indicates a base of any usual or preferred form, 2 a seat frame, and 3 a back frame. These frames of course may be made of any shape and size properly acting together and for acting as seat frames 70 and back frames, and also as means for defining a bed when moved to the position shown in Fig. 7.

A hinge for each side of the frames 2 and 3 is provided, but as the same are of identical construction a description of one will suffice for both. As clearly shown in the drawings, the hinge 4 is formed of three members, namely a leaf or plate 5, a leaf 6, and a pintle 7. By means of these hinges 80 the frames 2 and 3 are mounted so as to pivot freely in respect to each other, but are guided and controlled by a pawl 8 and by links 9 and 10. The link 9 is pivotally connected at 11 to the back 3 and at 85 12 to the rear part of the base 1. The link 10 is journaled on the pintle 7 and is pivoted at 13 to the base 1, the pivotal member 13 being preferably set back toward the rear beyond the center of the base. By this 90 construction and arrangement it will be observed that the links 9 and 10 are spaced some considerable distance apart at the bottom and close together at the top. This causes the weight of the frames 2 and 3 to 95 rest principally on the links 9 and 10 when it is desired to turn the frames from the position shown in Figs. 1 and 2, to the position shown in Fig. 7.

The pawl 8 is pivoted at 14 to the leaf 5 100 on the seat 2 and extends substantially in a horizontal line toward the rear until the same engages a stop 15. The stop 15 is connected with an extension of the leaf 6 so that the pawl may hold the back at any desired angle. At the rear end the pawl 8 is formed at a slight angle to its general direction and the angle portion is provided with a plurality of notches 16 which are designed to accommodate the stops. It will 110 be evident that any number of notches 16 may be provided for giving any desired ad-

justment to the back 3. The pawl 8 is pivoted at 14, but is permitted also a back and forth longitudinal movement by reason of the fact that it is provided with a slot 17 for accommodating the pivot pin. This back and forth movement is necessary in order to permit the pawl to move longitudinally when the cam surface 18 engages the stop 15, and when the cam surface 19 engages the stop 20. These cam surfaces engage the respective stops at the same time and by a continued pivotal movement of the seat the pawl will move longitudinally and finally permit a notch 21 to drop over the stop 20. This will lock the pawl 8 in an inoperative position, as clearly shown in Fig. 6. This locking of the pawl 8 is necessary when it is desired to move the back frame 3 and the seat frame 2, to the position shown in Fig. 7. As soon as the frames have reached approximately the position shown in Fig. 6, the upper edge of the pawl 8 engages a stop 22 projecting from the leaf 6. This will cause a disengagement of the stop 20 from the notch 21. When this has occurred the pawl drops down and rests on the smooth surface 23 against the stop 15. It remains in this position as long as the seat and back are left in the position shown in Fig. 7, but upon a pivotal upward movement of the seat 2, the same will slide over the stop 15 until the stop 15 has engaged in some of the notches 16. After this has occurred the seat 2 may then be forced downward against the base 1 which will cause the back 3 to move upward to the position shown in Figs. 1 and 2.

In operation, when the device is in the position shown in Figs. 1 and 2, and it is desired to raise the back to a more vertical position, the same may be done merely by pushing against the back until the same has reached the desired perpendicular. If it should be desired to transform the device into a bed, as shown in Fig. 7, the seat at any desired point, is grasped and raised pivotally to the position shown in Fig. 3, and then lowered to the position shown in Figs. 6 and 7, Fig. 6 showing an intermediate position. In adjusting the device from the position shown in Fig. 7, to that shown in Fig. 1, it is only necessary to raise the back to the desired angle and the seat will automatically slide to the rear according to the degree of angle of the back. By the construction and arrangement of the pawl 8 and the associated devices, the frames 2 and 3 may be adjusted to any desired position by merely shifting pivotally either the position of the seat or the back, as occasion may require, the pawl 8 acting automatically. Also by the arrangement of the links 9 and 10 the seat and back frames 2 and 3 are substantially evenly balanced so that it will require but little strength to adjust the device from acting as

a bed to a device which will act as a chair or davenport.

It will be noted that by the use of the links 9 and 10, and pivot pin, the working of the hinge is substantially noiseless. The pawl 8 is loosely mounted so that no binding will take place as the same moves from one position to another.

Having thus described my invention, I claim as new and desire to secure by Letters Patent:

1. A hinge for sofa beds comprising pivotally connected hinge members for attachment to the back frame and seat frame, respectively, of a sofa bed, a pivotally mounted pawl connected with the hinge member on said seat frame, said pawl being formed so as to have a longitudinal movement, a pin arranged on the hinge member on said back frame, a cam extending from said pawl acting on said pin for giving said pawl a substantially longitudinal movement, locking means engaging said pawl after the same has been moved longitudinally by said pin for holding the pawl in a locked position, and a stop for disengaging the pawl from said locking means.

2. A hinge for sofa beds comprising pivotally connected hinge members for attachment to the back frame and seat frame of a sofa bed, a pawl formed with a slot at one end, a pivotal pin projecting from the hinge member on said seat frame extending through said slot whereby the pawl is permitted a pivotal and longitudinal movement, said pawl being formed with a locking notch on one side, a plurality of notches on the opposite side and at the end opposite said slot, and a cam at the end opposite said slot, a locking pin projecting from the hinge member on the seat frame designed to at certain times engage said locking notch, a pin on the hinge member on the back frame for engaging the respective notches on said pawl at the end opposite said slot and for engaging said cam, said cam being adapted to act on said last mentioned pin and cause a longitudinal movement of the pawl whereby said locking pin and said locking notch are interlocked, and means on the hinge member on said back frame for disengaging the pawl from said locking pin.

3. A hinge for sofa beds comprising pivotally connected hinge members for attachment to the back frame and seat frame, respectively, of the sofa bed, a pawl pivotally mounted on one of said hinge members and engaging the other of said hinge members for locking the said frames together at any desired angle, said pawl being formed with a pair of cams, and a notch, means for acting on said cams for moving said pawl longitudinally, one of said last mentioned means being adapted to fit into said notch upon the return longitudinal movement of said

pawl, and means engaging said pawl for releasing said pawl from the means fitting in said notch.

4. A hinge for sofa beds comprising pivotally connected hinge members for attachment to the back frame and seat frame, respectively, of the sofa bed, a pawl formed with a longitudinal slot, a pin projecting from a hinge member on said seat frame 10 passing through said slot for pivotally supporting said pawl on said last mentioned hinge member, but permitting a longitudinal movement of the pawl, said pawl being formed with a plurality of notches at one 15 end on one side, and a notch on the opposite end to said first mentioned notches, a stop projecting from a hinge member on said back frame, adapted to engage any of said plurality of notches, a second pin projecting 20 from the hinge member on said seat frame adapted to engage the notch at the opposite end to said plurality of notches, means for moving said pawl against the action of gravity in a longitudinal direction until 25 said last mentioned notch has come opposite said last mentioned stop, whereby said last mentioned stop is permitted to engage said last mentioned notch for holding said pawl in an inoperative position, and means projecting from the hinge member on said back 30 frame for forcing said pawl to an operative position.

5. A hinge for sofa beds comprising pivotally connected hinged members for attachment to the back frame and seat frame, respectively, of the sofa bed, a pawl for locking said hinge members together at any desired angle, said pawl being formed with a slot at one end, a plurality of notches at the opposite end, a cam at the notched end of the pawl and a locking notch near the slotted end, a pin projecting from the hinge member on said seat frame fitting in said slot for pivotally supporting said pawl, a stop projecting from the hinge member on 40 said back frame arranged to engage any of said plurality of notches, and said cam, a stop arranged to fit into the notch formed in the slotted end of the pawl, said cam surface and said pawl engaging the stop on the 45 hinge member on said back frame, causing a longitudinal movement of said pawl for permitting the same to move into such a position as to cause said pawl to be locked in an inoperative position by said stop, and means engaging said pawl for moving the 50 same to an operative position.

In testimony whereof I have signed my name to this specification in the presence of two subscribing witnesses.

JOHN SONTHEIMER.
